Primary Examiner — Robin V Webster

Assistant Examiner — James C Thorn, Sr.

(57) **CLAIM**

The ornamental design for a hand slicer, as shown and described.

DESCRIPTION

FIG. 1 is an exploded view of the front, top and left side perspective view of a hand slicer;

FIG. 2 is a front exploded view thereof;

FIG. 3 is back side view thereof;

FIG. 4 is a top exploded view thereof;

FIG. 5 is a bottom view thereof;

FIG. 6 is a left side view thereof; and,

FIG. 7 is a right side view thereof.

The broken lines in the drawings are for the purpose of illustrating unclaimed portions and form no part of the claimed design.

1 Claim, 5 Drawing Sheets(56)
